HEATING AND AIR CONDITIONING
APPARATUS

Robert E. Daly, Bronxville, and Bernard Goerg, Scarsdale, N. Y., assignors, by mesne assignments, to American Radiator & Standard Sanitary Corporation, New York, N. Y., a corporation of Delaware

Application October 19, 1938, Serial No. 235,738

11 Claims. (Cl. 237—19)

Our invention relates to apparatus for supplying both heat and humidity to the air in room spaces and also for supplying hot tap water for domestic use, the present application being a division of our copending application, Serial No. 173,760, filed November 10, 1937.

An object of our invention is to provide apparatus of the above type which is simple and inexpensive in construction and which operates in an improved and efficient manner.

A further object is to provide a unitary attachment for use with domestic boilers of standard design, which functions to supply humidity in sufficient quantities to the air in the rooms already heated by such boilers.

A still further object is to provide a unitary attachment for standard household boilers which functions both to supply humidity to the air in the rooms and to supply hot water for domestic use.

The invention consists in the novel construction and combination of parts, to be more fully described hereinafter, and the novelty of which will be particularly pointed out and distinctly claimed.

In the accompanying drawings, to be taken as a part of this specification, we have fully and clearly illustrated a preferred embodiment of our invention, in which—

Fig. 1 is a fragmentary vertical section through a part of the basement and ground floor of a conventional house and showing in elevation our improved apparatus for air conditioning the house and for supplying hot water for domestic use;

Fig. 2 is an enlarged fragmentary vertical section through a boiler and enclosing jacket therefor and showing our improved humidifying and water heating device more in detail; and

Fig. 3 is a horizontal or plan section taken on the line 3—3 of Fig. 2.

Referring now in detail to the construction illustrated, it will be noted that we have shown our invention as installed within a building which may be of any desired type; for example, the conventional dwelling house. We have shown two rooms 10 and 11 of the building and a basement space 12 beneath the rooms.

We have shown a heating system for the rooms 10 and 11 which comprises a boiler 13 of conventional design located with the basement space 12, and radiators 14 and 15 located within the rooms 10 and 11, respectively, and connected to the boiler by supply and return pipes 16 and 17. Any desired heating fluid may be used to transmit the heat generated in the boiler 13 to the radiators 10 and 11; for example, hot water or steam. We have also shown outlet boxes 19 and 20 located within the walls of the rooms for supplying

humidified air thereto, in a manner which will appear more fully hereinafter.

Arranged also in the basement space is a hot water storage tank 22 forming a part of a system for supplying domestic hot water to the 5 bathroom, lavatories, etc. (not shown) usually located within the building. A hot water supply pipe 23 leads from the tank 22 and is adapted to be connected in the well known manner to the usual hot water taps (not shown). The usual 10 cold water supply pipe for the hot water system is indicated at 24.

In accordance with the present invention, we also provide a combined heat-exchange and humidifying device 25 which is constructed as a 15 separate unit and is detachably secured to the boiler 13. The unitary device 25 functions to supply humidified air to the rooms 10 and 11 through the outlet boxes 19 and 20, and also functions to heat the water for the domestic hot 20 water supply system. The device 25 is so constructed that it utilizes the heat of the fluid in the boiler 13, but to heat the domestic hot water and also to temper the humidified air before it is introduced into the rooms through the outlet 25 boxes. The device 25 is operatively connected to the hot water storage tank 22 by circulating pipes 27 and 28 and the humidified air outlet thereof is connected to the outlet boxes 19 and 20 by ducts 29 and 30, respectively.

In so far as the broader aspects of our invention are concerned, the unitary device 25 may be connected to any standard type of boiler having a service opening in a wall thereof communicating with the space therein containing the heating fluid. In the drawings, we have shown a boiler of the vertical sectional type having an opening 32 in the rear vertical wall 33 thereof in communication with the water space 34. The unitary device 25 closes the opening 32 and is 30 detachably secured to the wall 33 by suitable screws 36 (see Figs. 2 and 3). The entire boiler 13 and unitary device 25 is preferably enclosed by a jacket 37 of pleasing appearance, and the latter is so constructed that it provides with the rear wall 33 an enclosed space 38 for housing the unit 25.

The details of construction of the unitary device 25 are shown more clearly in Figs. 2 and 3. As shown, the device 25 comprises a box-like casting 40 which is open at one side thereof and communicates directly with the water space 34 through the opening 32 in the wall 33. The screws 36 serve to rigidly attach the casting 40 to the wall 33. The casting 40 comprises vertical walls 41, 42 and 43, and top and bottom walls 44 and 45, which define a chamber 46 in open communication with the space 34 and through which the boiler water from the space 34 circulates.

The device 25 also comprises a hot water heating coil 48 including end pipe connections 49 and 50, which extend through and are secured to the wall 42 of the casting 40 and thereby serve to support the coil 48 partially within the chamber 46 and partially in the water space 34 of the boiler. The ends of the connections 49 and 50 are firmly secured to the outer wall 42 by means of clamping nuts 51. Thus, the coil 48 is carried by the casting 40 and is insertable and removable therewith as a unit. The end connections 49 and 50 are connected respectively to the ends of the water circulating pipes 27 and 28 which, as previously described, form a part of the domestic hot water supply system.

The unitary device 25 also comprises an enclosing casing structure 53 secured by screws 52 to the casting wall 42. The casing 53 comprises a top wall 54, bottom wall 55 and side walls 56 and 57, and end walls 58 and 59. The casing 53 and casting 40 are so constructed that when they are assembled, the end wall 59 of the casing is spaced from a recessed portion 60 of the wall 42 and defines therewith an open-ended passage 61 for the flow of air. The interior of the casing structure 53 is provided with a horizontal partition 62 which divides the casing into an upper chamber 63, housing a blower 64 and the usual electrical control devices, and a lower chamber 65 for humidifying the air flowing therethrough.

The inlet of the blower 64 is connected to one end of an inlet duct 67 which extends through an opening in the wall 58 and communicates at its outer end with an air supply casing 68, an opening 69 in the jacket 37 providing the connection between the duct 67 and the casing 68. The air supply casing structure 68 is arranged within the basement space and may be provided with a suitable filter 70 for extracting foreign particles from the basement air flowing thereto and into the inlet of the blower. If desired, a connection may be provided between the casing 68 and the outside atmosphere for fresh air supply, or the casing 68 may be connected to the room for recirculated air supply. The outlet of the blower is indicated at 71 and communicates through an opening in the partition wall 62 with the humidifying chamber 65. The end wall 59 is provided with an opening 72 which serves as an outlet for the humidifying chamber 65 and as an inlet for the passage 61.

The end wall 59 is provided at its upper end with an opening 73 which serves as an outlet for the passage 61, and short vertical and horizontal partition walls 74 and 75, respectively, provide an outlet manifold 76 through which the humidified air flows from the passage 61 to the lower ends of the ducts 29 and 30, which, as stated above, are connected at their upper ends to the outlet boxes 19 and 28, respectively, in the rooms.

Arranged within the humidifying chamber 65 is a means for adding moisture to the air flowing therethrough. In so far as the broader aspects of our invention are concerned, this means may be of any suitable construction and operation. In the preferred embodiment shown, we have indicated this means as comprising a water spray device 78, comprising a nozzle 79 and a target 80 carried by the outer end of a rod 81 which is secured at its inner end to the nozzle casing 82. The nozzle ejects a fine stream of water toward the center of the target 80 which breaks up the stream in the form of a fog or

mist, as is well known. The rod 81 may be adjusted lengthwise to vary the distance between the target 80 and the nozzle 79 and thereby regulate the fineness of the spray. The water spray device 78 is secured to a detachable plate 84 forming a part of the end wall 58 of the casing and is connected by a pipe 85 to a suitable source of water supply. We prefer that the pipe 85 be connected to the circulating pipe 28 of the hot water supply system so that the spray water will be hot and thereby increase the humidifying capacity of the spray.

Connected in the pipe 85 is a solenoid valve 86 and strainer 87 and forming a part of the pipe 85 is a coil section 89. The strainer 87 serves to remove foreign particles from the water flowing to the spray which might clog the spray. The solenoid valve 86 may be connected into a suitable control system and operate to turn on and off the spray with the turning on and off of the oil burner (not shown) which fires the boiler 13, or if desired, the valve 86 may be operated in response to a humidity responsive instrument (not shown). The coil 89 permits the plate 84 and spray device 78 to be readily removed for cleaning and adjustment without disturbing the connection between the pipe 85 and circulating pipe 28.

The interior surfaces of the casting wall 42 are preferably formed with heat absorbing fins 90 which are arranged parallel with one another and extend in the general direction of flow of the boiler water through the chamber 46. Also, we provide on the exterior surface of the wall 42, a plurality of fins 91 formed integral with the wall and arranged parallel to one another and extending in the direction of flow of air through the passage 61. The fins 90 are preferably arranged opposite the fins 91. The fins 90 and 91 aid materially in the transfer of the heat from the boiler water to the air in the passage 61.

With the spray device 78 and the blower 64 operating, the humidifying chamber 65 is completely filled with a finely divided mist or fog from the spray nozzle 79, and the air flowing through the chamber from the blower will be practically saturated, and, in addition, will entrain therein a portion of the unabsorbed fog or mist. The stream of humidified air with the unabsorbed mist entrained therein flows into the passage 61 which is being constantly heated by the finned outer surface of the defining wall 42. As the stream becomes heated by contact with the wall 42, unabsorbed entrained particles of moisture will evaporate or become absorbed and the stream will be tempered and superheated. The humidified and heated air flows from the passage into the manifold 76 and then into the room through the ducts 29 and 30 and outlet boxes 19 and 28. The superheating or tempering of the air after humidification serves to prevent condensation of moisture in the ducts 29 and 30 and permits the introduction of the humidified air into the room spaces without discomfort to the occupants. Any water not evaporated in the chamber 65 and not absorbed by the air as it passes through the passage 61 drains down into a pocket 94 formed in the lower part of the wall 42 of the casting 40. A suitable drain pipe 95 is connected to the pocket 94 and serves to conduct away this excess water to any suitable point of disposal.

From the above, it will be appreciated that we have provided a simple, compact and inexpensive

form of apparatus which performs the triple purpose of heating the air in the room spaces, of supplying humidity to such air, and of supplying hot water to the hot water taps for personal use. It will also be observed that an important part of this inexpensive structure is the unitary device 25 which operates both as a built-in hot water heater and also as a humidifying and tempering means for humidified air. In prior art systems for supplying humidified air, there is usually provided a separate tempering coil at the down stream side of the humidifier. In the prior art hot water heating systems there is usually provided a separate heat-exchanger for heating the hot water. The usual separate tempering coil and the separate heat-exchanger have been eliminated in the present apparatus, as we provide a single unitary device for performing these two functions. Considered in one sense, it may be said that we utilize the heat which is normally lost to the atmosphere in the built-in type of hot water heaters of the prior art to perform the function of tempering and superheating the humidified air.

25 In another sense, it may be considered that we have provided a single unitary attachment which may be readily installed in a standard boiler having a service opening and which attachment functions both as a domestic hot water heating device and as a means for supplying tempered and humidified air to the rooms. The wall 42 of the casting 40 serves as a support for both the hot water coil 48 and the casing 53. The boiler water circulating through the chamber 46 defined in part by the wall 42, heats the water in the coil 48 and also tempers and superheats the humidified air flowing through the passage 61 also defined in part by the wall 42.

What we claim and desire to secure by Letters 40 Patent of the United States is:

1. The combination with a boiler having a space containing a fluid for heating rooms and an opening in a wall thereof communicating with said space, of a unitary attachment for said boiler operable to supply hot water for domestic use and to supply humidified air for comfort of the occupants of said rooms and comprising wall means detachably secured to said boiler and closing said opening in the boiler wall with its inner surface in contact with the boiler heating fluid; a coil for heating domestic hot water carried by said wall means and immersed in the boiler heating fluid; a casing structure carried by said wall means and including a wall arranged in spaced relation with the exterior surface of said wall means to define therebetween an open-ended air passage; said casing also including walls defining a chamber communicating with one end of said passage; air-humidifying means in said chamber; a blower providing for the flow of air first through said chamber and then through said passage; and conduit means connecting the discharge end of said passage with said rooms.

2. The combination with a boiler having a space containing a fluid for heating rooms and an opening in a wall thereof communicating with said space, of a unitary attachment for said boiler operable to supply hot water for domestic use and to supply humidified air for comfort of the occupants of said rooms and comprising wall means detachably secured to said boiler and closing said opening in the boiler wall with its inner surface in contact with the boiler heating fluid; a coil for heating domestic hot water carried by said wall means and immersed in the

boiler heating fluid; a casing structure carried by said wall means and including a wall arranged in spaced relation with the exterior surface of said wall means to define therebetween an open-ended air passage; said casing also including walls defining a blower chamber and walls defining a humidifying chamber connected at one side to said blower chamber and at its other side to one end of said air passage; a water spray device in said humidifying chamber; a blower in said blower chamber and providing for the flow of air through said humidifying chamber and then through said passage; and conduit means connecting the discharge end of said passage with said rooms.

3. In apparatus of the character described, the combination of a system for supplying heat to room spaces and including a boiler containing a heating fluid; a hot water supply system, a heat-exchange device secured to said boiler and comprising walls defining a chamber having an open side communicating directly with the interior of the boiler so that said heating fluid circulates through said chamber, and a tubular heat-exchanger arranged within said chamber and having pipe connections extending through a defining wall of said chamber and connected to said hot water system; a wall spaced from the exterior surface of a defining wall of said chamber to provide an air passage therebetween; a humidifying chamber having an outlet connected to one end of said passage; a conduit means connecting the other end of said passage with the room spaces; and means providing for the flow of air serially through said humidifying chamber, said passage, and said conduit means.

4. In apparatus of the character described, the combination of a system for supplying heat to room spaces and including a boiler containing a heating fluid and having an opening in a wall thereof communicating directly with the interior thereof; wall means detachably secured to said boiler for closing said opening and having its interior surfaces contacted by said heating fluid; a hot water supply system; a hot water heating coil carried by said wall means and having its exterior surface contacting with said heating fluid; a wall spaced from the exterior surface of said wall means and defining therewith a passage for air; a humidifying chamber having an outlet for humidified air connecting with one end of said passage; conduit means connecting the other end of said passage with said room spaces; and means providing for the flow of air serially through said humidifying chamber, said passage, and said conduit means.

5. In apparatus of the character described, the combination of a system for supplying heat to room spaces and including a boiler containing a heating fluid and having an opening in a vertical side portion thereof and communicating directly with the space containing said heating fluid; means including a vertical wall detachably secured to the boiler for closing said opening; a hot water supply system; a tubular heat-exchanger arranged with its exterior surface in contact with said heating fluid and having inlet and outlet conduit connections at the ends thereof extending through said vertical wall for supporting said heat-exchanger thereby, said conduit connections being connected to said hot water supply system; a wall spaced from the exterior surface of said vertical wall and defining therewith a passage for air; a humidifying chamber having an outlet for humidified air connected to

one end of said passage; conduit means connecting the other end of said passage with said room spaces; and means providing for the flow of air serially through said humidifying chamber, said passage, and said conduit means.

5 6. In apparatus of the character described, the combination of a system for supplying heat to room spaces and including a boiler containing a heating fluid and having an opening in a vertical side portion thereof and communicating directly with the space containing said heating fluid; means including a vertical wall detachably secured to the boiler for closing said opening; heat-absorbing fins on the interior surface of said vertical wall and contacting with said heating fluid; heat dissipating fins on the exterior surface of said vertical wall; a hot water supply system; a tubular heat-exchanger arranged with its exterior surface in contact with said heating fluid and having inlet and outlet conduit connections at the ends thereof extending through said vertical wall for supporting said heat-exchanger thereby, said conduit connections being connected to said hot water supply system; a wall spaced from the exterior surface of said vertical wall and defining therewith a passage for air; a humidifying chamber having an outlet for humidified air connected to one end of said passage; conduit means connecting the other end of said passage with said room spaces; and means providing for the flow of air serially through said humidifying chamber, said passage, and said conduit means.

7. In apparatus of the character described, the combination of a heating system for room spaces comprising a boiler containing a heating fluid and having an opening therein; a jacket enclosing at least a part of said boiler and spaced from that part of the boiler containing the opening to provide an enclosed space outside of the boiler walls; wall means within said space and detachably secured to said boiler for closing said opening and having its interior surface contacted by said heating fluid; a casing structure within said space and detachably secured to the outside of said wall means and including a wall spaced from the exterior surface of said wall means to define therewith a passage for air; air humidifying means within said casing structure and having an outlet connected to one end of said passage; conduit means connecting the other end of said passage with said room spaces; and means providing for the flow of air through said humidifying chamber, said passage, and said conduit means.

8. In apparatus of the character described, the combination of a heating system for room spaces comprising a boiler containing a heating fluid and having an opening therein; a jacket enclosing at least a part of said boiler and spaced from that part of the boiler containing the opening to provide an enclosed space outside of the boiler walls; wall means within said space and detachably secured to said boiler for closing said opening and having its interior surface contacted by said heating fluid; a casing structure within said space and detachably secured to the outside of said wall means and including a wall spaced from the exterior surface of said wall means to define therewith a passage for air open at its ends; said casing structure including walls defining a chamber having an inlet opening and having an outlet opening communicating with one end of said passage; a water atomizing device

in said chamber; conduit means connecting the other end of said passage with said room spaces; and a motor-driven blower within said space and having an outlet connected to the inlet of said chamber.

9. In apparatus of the character described, the combination of a heating system for room spaces comprising a boiler containing a heating fluid and having an opening therein; a jacket enclosing at least a part of said boiler and spaced from that part of the boiler containing the opening to provide an enclosed space outside of the boiler walls; wall means within said space and detachably secured to said boiler for closing said opening and having its interior surface contacted by said heating fluid; a tubular heat-exchanger carried by said wall means and arranged with its exterior surface in contact with said heating fluid; a hot water supply system connected to said tubular heat-exchanger; a casing structure within said space and detachably secured to the outside of said wall means and including a wall spaced from the exterior surface of said wall means to define therewith a passage for air open at its ends; air humidifying means within said casing structure and having an outlet connected to one end of said passage; conduit means connecting the other end of said passage with said room spaces; and means providing for the flow of air through said humidifying chamber, said passage, and said conduit means.

10. The combination with a boiler having a space containing a fluid for heating room spaces and having an opening in a wall thereof communicating with said space, of a humidifier attachment for said boiler comprising wall means closing said opening and detachably secured to said boiler wall with the inner surface of said wall means being in contact with the boiler heating fluid; a casing carried by said wall means and including a wall spaced from the exterior surface of said wall means to provide therebetween an open-ended air passage, and walls defining an air-humidifying chamber communicating with one end of said air passage; a blower providing for the flow of air first through said humidifying chamber and then through said passage; and conduit means connecting the discharge end of said passage with the rooms.

11. The combination with a boiler having a space containing a fluid for heating room spaces and having an opening in a wall thereof communicating with said space, of a humidifier attachment for said boiler comprising wall means closing said opening and detachably secured to said boiler wall with the inner surface of said wall means being in contact with the boiler heating fluid; a casing carried by said wall means and including a wall spaced from the exterior surface of said wall means to provide therebetween an open-ended air passage, walls defining an air-humidifying chamber communicating with one end of said passage, and walls defining a blower chamber communicating with said air-humidifying chamber; a blower in said blower chamber and providing for the flow of air first through said humidifying chamber and then through said passage; and conduit means connecting the discharge end of said passage with the rooms.
